UNITED STATES PATENT OFFICE.

SAMUEL MOORE, OF CLEVELAND, OHIO, ASSIGNOR OF ONE-THIRD TO ROBERT T. WISE,
OF CLEVELAND, OHIO, AND ONE-THIRD TO WILLIAM MILLER, OF FAIRMONT, WEST
VIRGINIA.

LOCOMOTIVE HEADLIGHT.

Application filed January 5, 1927. Serial No. 159,177.

This invention relates to headlight mechanism designed chiefly for locomotives, whereby to throw the rays of light on the track ahead of the engine, or train, when 5 making a turn or rounding a curve.

The invention utilizes the movement of the pilot truck of the locomotive as means for operating the mechanism to turn the headlight to the right or to the left, as 10 occasion may require to insure the lighting up of the track ahead a safe distance.

The invention provides a mechanism which may be readily installed upon locomotive engines in service without necessitating any 15 change in the construction or arrangement of parts and without entailing any very great expense consistent with the desired advantages.

While the drawings illustrate a preferred 20 embodiment of the invention, it is to be understood that in adapting the means to meet specific needs and requirements, the design may be varied and such other changes in the minor details of construction may be re- 25 sorted to within the scope of the invention as claimed, without departing from the spirit thereof.

For a full understanding of the invention 30 and the merits thereof, reference is to be had to the following description and the drawings hereto attached, in which,—

Figure 1 is a fragmentary view of the forward portion of a locomotive engine provided with a headlight mechanism embodying the invention, the pilot truck being in 35 section.

Figure 2 is a view of the pilot truck as seen from below.

Figure 3 is a detail sectional view on the 40 line 3—3 of Figure 2 looking in the direction of the arrows.

Figure 4 is an enlarged sectional detail on the line 4—4 of Figure 2, looking in the direction of the arrows.

45 Corresponding and like parts are referred to in the following description and designated in the several views of the drawings by like reference characters.

A sufficient amount of the front portion 50 of a locomotive engine is illustrated to demonstrate the application of the invention, the numeral 1 designating the boiler, 2 one of the cylinders, and 3 the pilot truck which is of the floating type to receive a lateral and

a tilting movement. A pillow block 4 rises 55 from the frame of the pilot truck and engages a rocker bearing 5 provided upon the bottom side of the engine, and in this manner the forward portion of the locomotive is supported upon the pilot truck to admit 60 of the latter having a relative tilting and pivotal side movement.

A vertical post 6 is located forwardly of the boiler 1 and is mounted in suitable bearings provided upon the front of the boiler 65 and the truck structure upon which the boiler and cylinders are mounted. The headlight 7 is mounted upon the post 6 to turn therewith and is adjustable vertically thereon so as to be located at the required elevation. An arm 8 is clamped or otherwise secured to the lower end of the post 6 and projects laterally and is pivoted to the laterally curved end 8^a of a longitudinally disposed bar 9 arranged beneath the top portion 70 of the pilot truck. The numeral 10 designates the pivot connection between the arm 8 and the lateral extension 8^a of the bar 9, and provision is had for adjusting the same by providing a plurality of openings 75 in one of the parts, as indicated most clearly in Figure 2.

A king bolt 11 or like part, projects downwardly from the sub-structure of the locomotive, and a bar 12 is pivotally mounted thereon adjacent one end, the opposite end of said bar being pivoted to the top portion of the truck frame, as indicated at 13. The adjacent ends of the bars 9 and 12 project laterally in the same direction as indicated 80 at 14 and 15, and are pivotally connected at their extremities, as indicated at 16. As a result of this arrangement a relative lateral movement of the pilot truck 3 effects 85 a pivotal movement of the bar 12 and a longitudinal movement of the bar 9, and since the latter is pivotally connected to the arm 8 the latter receives a pivotal movement which results in a turning of the post 6 and the headlight 7 mounted thereon. The parts 90 are of such construction and relative arrangement as to effect a turning of the headlight to insure the rays of light therefrom being projected upon the track in advance of the locomotive to enable the engineer to observe the roadway a safe distance ahead when bearing to the right or to the left from 95 a direct course.

Having thus described the invention, I claim:

1. The combination with the framework of a locomotive engine and the pilot truck, of a headlight pivotally mounted upon the framework, a longitudinal bar pivoted at its ends to the pilot truck and framework, respectively, and having a lateral extension at the end pivoted to the framework, and a longitudinally movable member extending lengthwise of the truck and provided at its ends with lateral extensions, one of which is pivoted to the lateral extension of the said bar and the other having connection with the headlight to effect a pivotal movement thereof.

2. The combination with the framework of a locomotive engine and the pilot truck, of a post pivoted to the framework, a headlight on the post, an arm projecting laterally from the post, a longitudinal bar pivoted at one end to the truck and at its opposite end to the framework and extended laterally, and a longitudinally movable member having end lateral extensions, one of said lateral extensions being pivoted to the arm of the post, and the other lateral extension being pivoted to the lateral extension of the longitudinal bar.

In testimony whereof I affix my signature.

SAMUEL MOORE. [L.S.]
